(57) **CLAIM**

We claim the ornamental design for a solid end mill, as shown and described.

DESCRIPTION

FIG. 1 is a perspective top view of a solid end mill showing the first embodiment of our new design;

FIG. 2 is a side view of the solid end mill of FIG. 1;

FIG. 3 is a top view of the solid end mill of FIG. 1;

FIG. 4 is a bottom view of the cutting insert and bolster of FIG. 1;

FIG. 5 is a perspective top view of a solid end mill showing the second embodiment of our new design;

FIG. 6 is a side view of the solid end mill of FIG. 5;

FIG. 7 is a top view of the solid end mill of FIG. 5;

FIG. 8 is a bottom view of the cutting insert and bolster of FIG. 5;

FIG. 9 is a perspective top view of a solid end mill showing the third embodiment our new design;

FIG. 10 is a side view of the solid end mill of FIG. 9;

FIG. 11 is a top view of the solid end mill of FIG. 9; and, FIG. 12 is a bottom view of the cutting insert and bolster of FIG. 9.

The broken line showings of FIGS. 1-12 are included for the purposes of illustrating portions of the solid end mill and form no part of the claimed design.

1 Claim, 9 Drawing Sheets
